The ornamental design for a beverage cartridge, as shown and described.

DESCRIPTION

FIG. 1 is a top, front, right perspective view of a beverage cartridge according to our new design;

FIG. 2 is a bottom, front, left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dashed broken lines in the figures illustrate portions of the beverage cartridge that do not form part of the claimed design. The dot-dash broken lines shown in the figures define bounds of the claim and form no part thereof.
